CLAIM

I claim the ornamental design for an H-style orchard float, as shown and described.

DESCRIPTION

FIG. 1 is a perspective view of an H-style orchard float showing my new design;

FIG. 2 is another perspective view thereof;

FIG. 3 is a top plan view thereof defining cross sectional plane 9-9;

FIG. 4 is a bottom plan view thereof;

FIG. 5 is a right side elevation view thereof;

FIG. 6 is a left side elevation view thereof;

FIG. 7 is a rear elevation view thereof; and

FIG. 8 is a front elevation view thereof; and,

FIG. 9 is a cross sectional view taken from cross sectional plane 9-9 defined in FIG. 3.
